UNITED STATES PATENT OFFICE.

HARRY U. MORTON, OF CHICAGO, ILLINOIS.

CAR-SHEATHING.

No. 920,981.

Specification of Letters Patent.

Patented May 11, 1909.

Application filed July 17, 1908. Serial No. 444,043.

To all whom it may concern:

Be it known that I, HARRY U. MORTON, a citizen of the United States, residing at Chicago, in the county of Cook and State of Illinois, have invented certain new and useful Improvements in Car - Sheathing, of which the following is a specification.

In certain styles of car construction, it is the present practice to sheath the car with flat metal plates, which are riveted or otherwise secured to the sides of the car in such manner as to expose the rivet heads, which practice is objectionable, for the reason that difficulty is experienced in cleaning the surface of the car, owing to the projection of the rivet heads, which furthermore are exposed to rust and the action of the elements, by reason of the irregularities in the exposed surface of the sheathing, due to the method of inserting the rivets. Furthermore, a car constructed in this manner is unsightly and presents a crude appearance as compared with wooden sheathed cars of the ordinary type.

The object of the present invention is to so construct and apply the sheathing that the rivet heads will be entirely concealed, thereby greatly improving the appearance of the car and at the same time serving to protect the rivets against the action of the elements and preventing the lodgment of dirt or the formation of rust around the rivet heads.

The invention consists in the features of construction and combination of parts hereinafter described and claimed.

In the drawings, Figure 1 is a side elevation of the end of the car, having the sheathing of the present invention applied thereto; Fig. 2 a perspective sectional view, showing the formation of the sheathing, the belt rail and the lower finishing strip; Fig. 3 a side elevation, showing the abutting ends of the two sections of sheathing with an insert applied thereto; and Fig. 4 a sectional view, taken on line 4—4 of Fig. 3.

The sheathing is in the form of a plurality of metal plates 5—5, which, in ordinary practice, are about six feet long, each of the plates being provided, along its upper edge, with an offset 6, leaving an overhanging shoulder 7. The plate, along its lower edge, is provided with a similar offset 8, leaving an overhanging shoulder 9. The plates are formed to provide offset edges 10, leaving overhanging shoulders 11. The offset edges thus provided at the top and bottom and

ends of the plates provide depressed flat attaching edges, which are provided with rivet holes 12, through which are entered suitable bolts or rivets for securing the sheathing to the car body. The rivet heads, along the top edge of the plates, are concealed and protected by the belt rail 13 of the car, the lower edge of which terminates in an inwardly projecting obliquely disposed flange 14 formed to underlie the overhanging shoulder 7. The upper portion 15 of the belt rail is formed to provide a sash rest for the windows, which upper portion terminates in a depending flange 16 which is secured by bolts or rivets to the frame of the car. The lower line of rivet heads, entered through the lower edges of the plates, is concealed by means of a protective strip 17, provided, on its upper edge, with an obliquely disposed inwardly extending flange 18 adapted to underlie the overhanging shoulder 9, and the strip is further provided, along its lower edge, with an inwardly extending flange 19, which is adapted to be bolted, riveted or otherwise secured to the under face of the lower portion of the frame of the car.

In applying the sheathing to the car, the plates or sections are riveted at the top, bottom and ends to the frame of the car, after which vertical inserts 20, having flaring sides 21, are inserted to overlie the abutting riveted ends of the plates, which, when the plates are brought together, afford a vertical channel of dovetailed formation, into which the inserts can be driven endwise in position to overlie and protect the rivet heads, and at the same time greatly improve the appearance of the car. The belt rail is applied in position to bring the inwardly extending flange 14 under the overhanging upper shoulder, after which the upper edge of the belt rail is secured to the frame of the car, which arrangement is such as to hold the belt rail against displacement at both top and bottom, and at the same time cover and protect the upper line of rivet heads. In like manner the lower protective strip 17 serves to cover and protect the lower line of rivet heads, and affords a neat and attractive finish for the lower edge of the sheathing, the in-turned flange 19 serving to underlie and protect the car against the ingress of moisture between the sheathing and the frame of the car.

The invention is one which adds greatly to

the appearance of the car, at the same time protecting the rivet heads at all points and permitting continuous plates to be employed in the sheathing of the car without any of 5 the attendant objections which have been previously found against sheathing of this general style.

What I regard as new and desire to secure by Letters Patent is:

10 1. In a car construction, the combination of a plurality of sheathing plates secured end to end to the frame of the car, each of the plates being provided, at its end, with an offset leaving an overhanging shoulder, the 15 two shoulders of adjacent plates affording a channel of dove-tailed formation, fastening means entered through the offset ends, and insert strips formed to dove-tail into the channels between the plates, substantially as 20 described.

25 2. In a car construction, the combination of a plurality of sheathing plates secured end to end to the frame of the car, each of the plates being provided, at its end, with an offset leaving an overhanging shoulder, the two shoulders of adjacent plates affording a channel of dove-tail formation, fastening means entered through the offset ends, and vertical insert strips provided with flaring 30 sides adapted to underlie the overhanging shoulders and dove-tail into the channels between the plates, substantially as described.

35 3. In a car construction, the combination of a plurality of sheathing plates secured end to end to the frame of the car, each of the plates being provided, at its end, with an offset leaving an overhanging shoulder, the two shoulders of adjacent plates affording a channel of dove-tailed formation, fastening means 40 entered through the offset ends, insert strips formed to dove-tail into the channels between the plates, each of the plates being provided with an offset upper edge affording an overhanging shoulder, fastening means 45 entered through said offset edge, a belt rail provided, along its lower edge, with a flange adapted to underlie the overhanging shoulder, and fastening means for securing the belt rail to the frame of the car, substantially 50 as described.

55 4. In a car construction, the combination of a plurality of sheathing plates secured end to end to the frame of the car, each of the plates being provided, at its end, with an offset leaving an overhanging shoulder, the two shoulders of adjacent plates affording a channel of dove-tailed formation, fastening means entered through the offset ends, vertical insert strips provided with flaring sides 60 adapted to underlie the overhanging shoulders and dove-tail into the channels between the plates, each of the plates being provided with an offset upper edge affording an overhanging shoulder, fastening means entered 65 through said offset edge, a belt rail provided,

along its lower edge, with a flange adapted to underlie the overhanging shoulder, and fastening means for securing the belt rail to the frame of the car, substantially as described.

5. In a car construction, the combination 70 of a plurality of sheathing plates secured end to end to the frame of the car, each of the plates being provided, at its end, with an offset leaving an overhanging shoulder, the two shoulders of adjacent plates affording a channel 75 of dove-tailed formation, fastening means entered through the offset ends, insert strips formed to dove-tail into the channels between the plates, each of the plates being further provided with an offset lower edge affording an overhanging shoulder, and a protective strip provided with an upper flange adapted to underlie said overhanging shoulder, and provided with an inturned lower flange adapted to be secured to the frame of 80 the car, substantially as described.

6. In a car construction, the combination 90 of a plurality of sheathing plates secured end to end to the frame of the car, each of the plates being provided, at its end, with an offset leaving an overhanging shoulder, the two shoulders of adjacent plates affording a channel 95 of dove-tailed formation, fastening means entered through the offset ends, vertical insert strips provided with flaring sides adapted to underlie the overhanging shoulders and dove-tail into the channels between the plates, each of the plates being further provided with an offset lower edge affording an overhanging shoulder, and a protective strip provided with an upper flange adapted to underlie said overhanging shoulder, and provided with an inturned lower flange adapted to be secured to the frame of the car, substantially as described.

7. In a car construction, the combination 100 of a plurality of sheathing plates secured end to end to the frame of the car, each of the plates being provided, at its end, with an offset leaving an overhanging shoulder, the two shoulders of adjacent plates affording a channel 110 of dove-tailed formation, fastening means entered through the offset ends, insert strips formed to dove-tail into the channels between the plates, each of the plates being provided with an offset upper edge affording an overhanging shoulder, fastening means entered through said offset edge, a belt rail provided, along its lower edge, with a flange adapted to underlie the overhanging shoulder, fastening means for securing the belt rail to the frame of the car, each of the plates being further provided with an offset lower edge affording an overhanging shoulder, and a protective strip provided with an upper flange adapted to underlie said overhanging shoulder, and provided with an inturned lower flange adapted to be secured to the frame of the car, substantially as described.

8. In a car construction, the combination 130

of a plurality of sheathing plates secured end to end to the frame of the car, each of the plates being provided, at its end, with an offset leaving an overhanging shoulder, the two 5 shoulders of adjacent plates affording a channel of dove-tailed formation, fastening means entered through the offset ends, vertical insert strips provided with flaring sides adapted to underlie the overhanging shoulders and 10 dove-tail into the channels between the plates, each of the plates being provided with an offset upper edge affording an overhanging shoulder, fastening means entered through said offset edge, a belt rail provided, 15 along its lower edge, with a flange adapted to

underlie the overhanging shoulder, fastening means for securing the belt rail to the frame of the car, each of the plates being further provided with an offset lower edge affording an overhanging shoulder, and a protective 20 strip provided with an upper flange adapted to underlie said overhanging shoulder, and provided with an inturned lower flange adapted to be secured to the frame of the car, substantially as described.
